ENGINE STARTING APPARATUS

Romeo M. Nardone, East Orange, N. J.

Original application February 19, 1929, Serial No. 341,164. Divided and this application November 2, 1934, Serial No. 751,227

3 Claims. (Cl. 127—179)

This invention relates to engine starting apparatus, and more particularly to starters of the type adapted to physically engage and rotate the engine crankshaft, or a connection leading therefrom.

One of the objects of the present invention is to provide novel starting mechanism including a booster magneto.

Another object is to provide novel cranking mechanism for internal combustion engines embodying means for automatically connecting the starter mechanism in driving relation with the engine to be cranked.

A further object is to provide novel engine cranking means of the type embodying means for protecting the operating person or agency against injury from a backfire of the engine. The above and other objects will appear more fully hereinafter in the detail description.

One embodiment of the present invention is illustrated in the accompanying drawing wherein like reference characters refer to like parts throughout the several views. It is to be expressly understood, however, that the drawing is for purposes of illustration only and is not designed as a definition of the limits of the invention, reference being had for this purpose to the appended claims.

In the drawing:

Figure 1 is an axial sectional view of one embodiment of the invention.

Figure 2 is a detail view of the meshing mechanism shown in Figure 1; and

Figure 3 is a detail view, partly in section, of the locking mechanism.

As shown, the starter housing comprises an outer section 69 adapted to be secured in any suitable manner to the engine crankcase 11. Attached to housing section 69 as by means of screws 70 is an inner section 71 in which is rotatably mounted as by means of bearings 72 a cranking shaft 73.

The outer end of the cranking shaft has drivably attached thereto a pinion 74 which meshes with an internal spur gear 75 having a hub 75a which is rotatably mounted in housing section 71. Gear 75 is drivably connected to a hollow cylindrical member 76 which is supported in the outer housing section 69. Preferably, a plurality of cap screws, one of which is shown at 9, are employed to connect the outer face of gear 75 with the inner end of cylindrical member 76. The latter is adapted to rotate an internally threaded sleeve 77 and, for reasons to be pointed out more fully hereafter, the driving connection between

these members is preferably constituted by a friction clutch embodying a plurality of disks 78. A number of said disks are splined to the outer surface of the cylindrical member 76 and the remaining disks are splined to sleeve 77. The outer end of member 76 is bent inwardly to provide a flange 79 which coacts with a flange 80 provided on the inner end of sleeve 77 to hold disks 78 in operative relationship. Preferably thrust washers 81 and 82 are interposed between the disks and the shoulders 80 and 79 respectively.

Yielding means are provided for varying the pressure with which the disks 78 are held in engagement. As illustrated, the outer surface of sleeve 77 is threaded to receive a nut 83 that has operative engagement with a plurality of coil springs 84 which are arranged in an annular series around sleeve 77 and bear at their inner ends against a washer 85 which has abutting engagement with flange 79 of the cylindrical member 76. By adjusting the position of nut 83 relative to sleeve 77 the compression of springs 84 and hence the pressure between disks 78 is varied.

Sleeve 77 is adapted to rotate a jaw clutch member 86 which is normally disengaged from but is adapted for movement into driving engagement with a similar jaw clutch member 87 carried by a rotatable member of the engine to be cranked, such as the engine crankshaft or an extension thereof. For this purpose there is positioned within sleeve 77 a threaded shaft 88 which carries on its inner end a stop nut 89 adapted to engage a shoulder 90 provided interiorly of sleeve 77. The outer portion of shaft 88 is longitudinally splined at 91 to engage corresponding splines formed interiorly of a laterally extending cylindrical portion 92 of jaw clutch member 86.

The starting mechanism embodies automatic means for moving jaw clutch member 86 into driving engagement with member 87, said means being rendered operative at the beginning of the cranking operation and being so constituted that the jaw clutch member 86 acts to return the parts to normal position after the engine starts under its own power. To this end there is provided a rod 93 which extends through jaw clutch member 86, shaft 88, and the hub portion 75a of gear 75. As shown, rod 93 is rigidly connected to shaft 88 for rotation therewith as by means of a pin 94. The outer end of rod 93 extends freely through a central opening in jaw clutch member 86 and is provided with a nut 95 for maintaining said member in operative relation with threaded shaft 88. A coil spring 96 surrounds

rod 93 and is interposed between threaded shaft 88 and the hub portion of clutch member 86.

Rigidly attached to rod 93 outwardly of hub 75a is a collar 97 having one or more teeth which 5 normally engage teeth 98 provided on a disk 99 which is slideable longitudinally relative to rod 93 but is held against rotation by means of a plate 100 that is attached by means of screws 101 to housing section 71 and is provided with 10 an opening through which teeth 98 loosely extend. Surrounding rod 93 and interposed between disk 99 and a collar 102 carried by the inner end of said rod is a coil spring 103 which 15 normally maintains disk 99 in engagement with the plate 100. Preferably a thin metal cover 104, which may be secured in position by the screws 101, surrounds the inner end of rod 93 and encloses spring 103 and disk 99.

Preferably oil seal means are provided for the 20 starting mechanism in order to prevent seepage of oil from the engine crankcase 11 into the starter housing 69, 71. For this purpose a light cup-shaped member 105 that is preferably formed of metal, is fitted over the outer end of the starter 25 that projects into the engine crankcase and is provided with a flange 106 adapted to be clamped between housing section 69 and the engine crankcase 11. At its outer end member 105 is provided with a central opening slightly larger in diameter than the outer diameter of jaw member 86 and in order to strengthen the metal at this point the same is bent to provide a curved lip 107. If desired, the flexible washer 53 shown in Fig. 2 may be associated with member 105. A pair of washers 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560

As above suggested, the invention includes means to prevent counter-rotation of cranking shaft 73 in the event that the engine backfires during the cranking operation and while jaw clutch member 86 is in engagement with jaw member 87. For this purpose housing section 69 of the starter may be provided with an opening 50 into which extends a cap 109, (Fig. 1) the cap being flanged as at 110 in order to facilitate its attachment to the housing by means of screws 111. Pivotally mounted within the cap 109 is a pawl 112 which is yieldingly held in engagement 55 with a ratchet wheel 113 constituted by teeth formed on the outer periphery of the internal gear 75. A suitable spring 114 yieldingly maintains pawl 112 in engagement with the ratchet wheel.

60 Normal rotation of the cranking shaft to effect the cranking operation causes rotation of the ratchet wheel in a direction such that pawl 112 rides freely over the ratchet teeth. If the engine backfires there is a tendency for gear 75 to be rotated in the opposite direction, but said gear is positively locked against rotation in this direction by means of pawl 112, thus preventing counter-rotation of cranking shaft 73. The friction clutch 78 permits relative rotation between 65 the parts whereby injury to the same is avoided.

The starting mechanism also includes a booster magnet 115 having an armature shaft 116 which is adapted to be rotated at high speed from the cranking shaft 73. For this purpose the latter is provided with a transversely extending

pin 117 which extends into longitudinal slots 118 in the cylindrical extension of a gear member 119 which is rotatably mounted in a gear case 120 secured in any suitable manner to the housing section 71. On its outer face gear member 119 is 5 provided with a laterally extending portion 121 carrying a transverse pin 122. Gear 119 meshes with a pinion 155 on a shaft 156 which also carries a gear 157, all of which constitute parts 10 of a suitable step-up gear train mounted in case 120, the high speed end 158 of the gear train being connected in any suitable manner to armature shaft 116.

When it is desired to crank the engine shaft 73 is rotated by suitable means, such as a hand 15 crank engageable with pin 122 of gear extension 121. The rotation of the shaft 73 is transmitted through pinion 14, gear 75, cylindrical member 16 and friction clutch 78 to sleeve 77. Rotation of the latter tends to rotate the shaft 88 20 and jaw clutch member 86 splined thereto. At this time, however, the teeth of collar 97 are in engagement with teeth 98 and rotation of shaft 88 is thus prevented, but due to the threaded engagement of the latter with sleeve 77, said 25 shaft moves to the left as viewed in Fig. 5, carrying therewith rod 93, spring 103 being compressed between disk 99 and collar 102. Simultaneously, spring 96 yieldingly moves clutch member 86 30 into full meshing engagement with clutch member 87 at which time the collar 97 has moved out of engagement with teeth 98 and stop nut 89 has engaged shoulder 90 provided interiorly of sleeve 77. Since the shaft 88 is now locked in engagement with sleeve 77 these parts rotate in unison 35 and this motion is transmitted through splines 91 to the jaw clutch member 86 whereby the engine crankshaft is rotated.

After the engine starts under its own power the 40 crankshaft rotates at a speed greater than that of jaw clutch member 86 whereupon the inclination of the teeth of said jaw members is effective to move member 86 to the right out of driving engagement with member 87. Spring 103 is now 45 effective to return rod 93, shaft 88 and jaw clutch member 86 to normal position. In the event that the teeth of collar 97 abut against the ends of teeth 98 the longitudinal movement of rod 93 is not prevented since spring 103 permits disk 99 50 and teeth 98 to be moved to the right. As soon as rod 93 has rotated through a small angular distance the ends of the teeth 97 and 98 will be 55 disengaged, whereupon spring 103 will return disk 99 into engagement with plate 100.

There is thus provided novel engine starting mechanism of the type embodying automatic means for moving the jaw clutch member, which is normally in non-driving position, into driving engagement with the engine to be started or 60 cranked. The apparatus may be so constructed as to be actuated from either side thereof or from a point in the rear. Means are provided for protecting the operating person or agency against 65 injury from a backfire of the engine.

The starter of the present invention is particularly adapted for use on aeroplane engines, but as will be understood by those skilled in the art, its use is not restricted thereto. Various changes may be made in the details of construction and arrangement and certain parts may be used without other parts. Reference will therefore be had to the appended claims for a 70 definition of the limits of the invention.

This application is a division of my co-pend- 75

ing application No. 341,164, filed February 19, 1929.

What is claimed is:

- 5 1. In combination with an engine engaging member and an actuating shaft rotatable about parallel axes, driving connections between said actuating shaft and engaging member including a second shaft having a splined connection with said engaging member and movable axially there-
10 with, a rod rotatable with said second shaft, a toothed collar on said rod, and means engageable with said collar to prevent rotation of said rod and second shaft during axial movement of the engine engaging member.
- 15 2. In combination with an engine engaging member and an actuating shaft rotatable about parallel axes, driving connections between said actuating shaft and engaging member including
- 5 a second shaft having a yieldable connection with said engine engaging member, a rod rotatable with said second shaft, and means surround-
10 ing said rod to oppose rotation of said second shaft during engine engaging movement of the engine engaging member.
- 15 3. In combination with an engine engaging member and an actuating shaft rotatable about parallel axes, driving connections between said actuating shaft and engaging member including a second shaft having a telescopic connection with said engine engaging member, a mesh con-
15 trolling part projecting from and rotatable with said second shaft, and means operating upon said projecting part to oppose rotation of said sec-
ond shaft during axial movement of the engine engaging member.

ROMEON M. NARDONE.
